(Cl. D23—1)

To all whom it may concern:

Be it known that we, Herman R. Dilger, Stanley E. Kline and Thomas M. Leonard, citizens of the United States, and residents of Waterloo, in the county of Black Hawk and State of Iowa, have invented a new, original, and ornamental Design for a Cream Separator, of which the following is a specification, reference being had to the accompanying drawing, form part thereof.

Fig. 1 is a front elevational view of a cream separator, showing our new design.

Fig. 2 is a side elevational view of one side of said cream separator.

Fig. 3 is a side elevational view of the other side of said cream separator, with a portion thereof broken away.

Fig. 4 is a rear elevational view of said cream separator; and

Fig. 5 is a top plan view of said cream separator.

We claim:

The ornamental design for a cream separator, as shown.

HERMAN R. DILGER,
STANLEY E. KLINE,
THOMAS M. LEONARD.
